Mich., a corporation of Delaware
No Drawing. Filed Aug. 27, 1963, Ser. No. 304,978
4 Claims. (Cl. 167—74)

This application is a continuation-in-part of application Ser. No. 114,621, filed June 5, 1961.

This invention relates to therapeutic compositions containing $7\alpha,17\alpha$ -dimethyltestosterone and to a method for their use.

In the treatment of clinical conditions calling for an increase in the storage of protein and the stimulation of tissue growth, the administration of anabolic agents is frequently beset by concomitant androgenic side effects in the agents employed. The development of male sexual characteristics in the course of anabolic therapy is a limiting factor with agents heretofore available.

Comparative studies have shown that $7\alpha,17\alpha$ -dimethyltestosterone (J. Am. Chem. Soc., 81:4069 [1959]) offers an unexpected split between anabolic and androgenic activities at therapeutically effective anabolic dosage levels. With this agent it is possible to provide anabolic therapy which is essentially free of undesirable androgenic side effects. This split in activity provides a sharp departure from related compounds in the art. For example, the anabolic/androgenic ratio as obtained in rigidly controlled, double cross-over studies of anabolic activity in monkeys and androgenic activity in rats is 1.9 for $7\alpha,17\alpha$ -dimethyltestosterone as compared with 1 for methyltestosterone, a commonly used standard. In humans, the anabolic potency is significantly greater than other commonly used anabolic steroids.

A temporary and useful repression of breast tumors is observed on therapy with this compound.

A daily oral dose of from about 0.25 to about 5 mg. per day of $7\alpha,17\alpha$ -dimethyltestosterone has been found to provide highly effective anabolic therapy essentially free of undesirable androgenic side effects. The same regimen is appropriate for clinical utilization of the anti-tumor activity described. The exact dosage schedule, of course, must be determined individually according to the subject's age, weight, response to the medication and severity of the condition being treated. In general, however, a regimen of about 0.01 to about 0.03 mg./kg. bodyweight/day is preferred for children and about 0.02 to about 0.08 mg./kg. bodyweight/day for adults.

In adapting the active ingredient for use in mammals, including humans, the novel compositions are suitably presented for administration in unit dosage form as tablets, pills, capsules, powders, wafers, cachets, granules, oral dispersions, and the like.

For preparing solid compositions such as tablets, the active ingredient in crystalline, powdered, or micronized form is mixed with a conventional tableting component such as lactose, cornstarch, dicalcium phosphate, terra alba (calcium sulfate), talc, stearic acid, calcium stearate, gums, and functionally similar materials constituting pharmaceutical diluents or carriers. The tablets or pills can be laminated or otherwise compounded to provide a dosage form affording the advantage of prolonged or delayed action or of predetermined successive action of the enclosed medication. For example, the tablet or pill can comprise an inner dosage and outer dosage com-

2

ponent, the latter being in the form of an envelope over the former. The two components can be separated by an enteric layer which serves to resist disintegration in the stomach and permits the inner component to pass intact into the duodenum or to be delayed in release. A variety of materials can be used for such enteric layers or coatings, such materials including a number of polymeric acids or mixtures of polymeric acids with such materials as shellac, shellac and cetyl alcohol, cellulose acetate phthalate and the like. A particularly advantageous sustained release coating comprises a styrene maleic acid copolymer.

The liquid forms in which the novel compositions of this invention can be incorporated include aqueous solutions or suspensions, as well as elixirs and similar pharmaceutical vehicles. Suitable dispersing or suspending agents for aqueous suspensions include the synthetic and natural gums such as tragacanth, acacia, dextran, methylcellulose, polyvinylpyrrolidone, gelatin and the like.

The term "unit dosage form" as used in the specification and claims herein refers to physically discrete units suitable as unitary dosages for human subjects, each unit containing a predetermined quantity of active material calculated to produce the desired therapeutic effect in association with the required pharmaceutical diluent, carrier or vehicle. The specification for the novel unit dosage forms of this invention are dictated by and directly dependent on (a) the unique characteristics of the active material and the particular therapeutic effect to be achieved and (b) the limitations inherent in the art of compounding such an active material for therapeutic use in humans, as disclosed in detail in this specification, these being features of the present invention. Examples of suitable unit dosage forms, as heretofore described, are tablets, capsules, pills, powder packets, wafers, cachets, granules, solutions or suspensions for oral use, suppositories, and segregated multiples of any of the foregoing, and other forms alluded to herein.

The following examples illustrate the best mode contemplated for carrying out this invention, but these examples are not to be construed as limiting the scope thereof.

EXAMPLE 1—TABLETS

45 A batch of 10,000 compressed tablets, each containing 1 mg. of $7\alpha,17\alpha$ -dimethyltestosterone, is prepared from the following ingredients:

	Gm.
7 α ,17 α -dimethyltestosterone	10
50 Lactose	40

The finely powdered steroid and lactose are thoroughly mixed and granulated with syrup-starch paste. Starch and calcium stearate are used as lubricants, and the tablets are compressed in the usual manner.

55 Administration of these tablets is on a schedule of 1 tablet daily for adults to stimulate weight gain.

EXAMPLE 2—TABLETS

60 In the formulation of Example 1, 2.5 gm. or 50 gm. can be substituted for the 10 gm. of $7\alpha,17\alpha$ -dimethyltestosterone to give tablets containing 0.25 mg. or 5 mg., respectively, which can be administered on the same schedule for anabolic therapy.

EXAMPLE 3—ORAL ANABOLIC ACTIVITY

This test was carried out using the method of Stucki et al., Endocrinology 66:585 (1960). Young adult female

monkeys were ovariectomized and acclimated to a balance ward of rigidly controlled environment. Each day the animals were offered 200 ml. of water and an amount of constant composition diet sufficient to permit slow weight gain if no anabolic agent were administered. During control and drug periods alike, each animal was given twice a day one sugar cube soaked in 0.6 ml. of a multiple vitamin preparation. Oral drug administration was accomplished by instilling the requisite amount of an alcohol solution of the test compound into the sugar cube several hours before it was soaked with the vitamin suspension and given to the animal.

All the animals were kept on balance continuously. Collection of faeces, urine and food remnants was made every other day at the time body weights were obtained. Homogenates of the collections were prepared and aliquots analyzed using a modified Kjeldahl procedure for total nitrogen and a flame photometer for potassium. Daily balance was calculated by comparison of these values with those obtained from food analyses.

In all experiments either a spot single point assay or a quantitative twin crossover assay design (Finney, Statistical Method in Biological Assay, 1952, p. 265; Hafner Publishing Co., New York) involving four monkeys or a double-twin crossover design involving eight monkeys was employed. In crossover experiments two doses of the standard, fluoxymesterone (9α -fluoro- $11\beta,17\beta$ -dihydroxy- 17α -methyl-4-androstene-3-one) and two doses of the test compound (based on results in preliminary spot assays) were employed. Each drug period was 10-14 days in length. The first drug period was preceded by a 10-14 day control period and similar control periods separated the two drug periods and followed the second drug period.

To determine the anabolic effect produced by a test compound, the average amount of nitrogen retained per day for the last eight treatment (pre- and post-drug control) days was calculated. The difference between pre-drug control and treatment values (Δ pre) and the difference between post-drug control and treatment values (Δ post) was then calculated for each monkey. By the use of appropriate statistical methods for the twin crossover assay, potency of the test drug was then calculated and expressed in terms of the standard (fluoxymesterone) for each parameter of nitrogen retention using Δ pre, Δ post- and on-drug values. Potassium balance data were similarly treated. Body weight gain during drug treatment was also used to calculate drug potency.

The average of all seven estimates of potency was then determined. By suitable conversion, potency can also be expressed in terms of other drugs, for example, methyltestosterone. Results obtained with quantitative double twin cross-over assays on $7\alpha,17\alpha$ -dimethyltestosterone and methyltestosterone are presented in the following table:

TABLE.—ANABOLIC POTENCIES OF $7\alpha,17\alpha$ -DIMETHYLTESTOSTERONE AND METHYLTESTOSTERONE RELATIVE TO STANDARD DRUG, FLUOXYMESTERONE

Parameter	Anabolic Potency (Percent of Fluoxymesterone)	
	Methyltestosterone	$7\alpha,17\alpha$ -dimethyltestosterone
Nitrogen retention:		
Δ pre.....	17	101
On dose.....	18	135
Δ post.....	31	121
Potassium retention:		
Δ pre.....	12	101
On dose.....	16	121
Δ post.....	34	104
Body weight gain.....	13	121
Average potency (percent of fluoxymesterone).....	20	115
Average potency (percent of methyltestosterone).....	100	575

EXAMPLE 4—ANDROGENIC ACTIVITY

The procedure employed was that described by Lyster et al., Endocrinology, 58: 781 (1956). The test animals were rats of the Upjohn-Sprague-Dawley colony which were castrated at 26 to 27 days of age. Beginning on the day following castration and continuing for 9 days, the animals were given orally a suspension of test compound in cottonseed oil in predetermined dosage. On the day following the last dosage the rats were sacrificed and the seminal vesicles (exclusive of coagulating gland and contained secretion) were weighed. Multiple point parallel line assays with 5 or more rats per point were used for quantitative potency estimates. The average weights of the seminal vesicles for the animals in each dosage level were determined and compared with results obtained using the standard, methyltestosterone. The androgenic activity of the test compound was expressed as a multiple of that of methyltestosterone. Results were as follows:

20	Androgenic activity	X methyltestosterone
	$7\alpha,17\alpha$ -dimethyltestosterone	3

EXAMPLE 5—ANABOLIC THERAPY

In clinical studies on over 200 humans, $7\alpha,17\alpha$ -dimethyltestosterone has produced the benefits of anabolic therapy at clinically effective doses of 0.25 to 5 mg. per day without significant signs of androgenicity (acne, voice change, hirsutism, etc.).

EXAMPLE 6—COMBINATION THERAPY

Where concomitant antibacterial therapy is desired, antibiotics, e.g., the tetracyclines (tetracycline, demethyltetracycline, oxytetracycline or chlortetracycline), can be employed in dosage units, e.g., comprising from about 0.25 to about 5 mg. of $7\alpha,17\alpha$ -dimethyltestosterone and from about 100 to about 250 mg. of tetracycline. An illustrative composition is as follows:

A lot of 1000 capsules, each containing 0.5 mg. of $7\alpha,17\alpha$ -dimethyltestosterone and 125 mg. of tetracycline (as tetracycline phosphate complex), is prepared from the following ingredients:

	Gm.
$7\alpha,17\alpha$ -dimethyltestosterone	0.5
Tetracycline phosphate complex	125
Starch, bolted	50
Calcium stearate	1
Talc	1

The starch, talc and calcium stearate are thoroughly mixed and the finely divided active ingredients incorporated into the mixture. The resulting material is milled, screened and filled into telescoping capsules by conventional methods. One capsule or more daily is given for combined anabolic and antibacterial therapy.

For more comprehensive antibacterial therapy in conjunction with anabolic therapy, from about 25 to about 250 mg. of novobiocin can be included in each capsule of the above formulation for similar administration.

What is claimed is:

1. A therapeutic composition comprising: in oral unit dosage form, from about 0.25 to about 5 mg. of $7\alpha,17\alpha$ -dimethyltestosterone, dispersed in a pharmaceutical carrier.
2. A therapeutic composition comprising: in oral unit dosage form, from about 0.25 to about 5 mg. of $7\alpha,17\alpha$ -dimethyltestosterone and from about 100 to about 250 mg. of tetracycline, demethyltetracycline, oxytetracycline, or chlortetracycline, dispersed in a pharmaceutical carrier.
3. A method for inducing anabolic effects in mammals essentially free of accompanying androgenic effects comprising: administering orally $7\alpha,17\alpha$ -dimethyltestosterone in an amount sufficient to induce anabolic effects but essentially free of accompanying androgenic effects.
4. A method for inducing anabolic effects in humans essentially free of accompanying androgenic effects com-

prising: administering orally from about 0.25 to about 5 mg. daily of 7 α ,17 α -dimethyltestosterone.
